RONALD A. McCANN, OF SWISSVALE, PENNSYLVANIA, ASSIGNOR TO UNION SWITCH & SIGNAL COMPANY, OF SWISSVALE, PENNSYLVANIA, A CORPORATION OF PENNSYLVANIA.

RAILWAY SIGNALING.

1,324,200.

Specification of Letters Patent.

Patented Dec. 9, 1919.

Application filed April 11, 1918. Serial No. 223,027.

To all whom it may concern:

Be it known that I, RONALD A. McCANN, a citizen of the United States, residing at Swissvale, in the county of Allegheny and State of Pennsylvania, have invented certain new and useful Improvements in Railway Signaling, of which the following is a specification.

My invention relates to railway signaling, and particularly to signaling for single track over which traffic moves in both directions. More specifically, my invention relates to means for controlling the signals adjacent the passing sidings in systems to the type specified.

I will describe one form of signaling embodying my invention, and will then point out the novel features thereof in claims.

In the accompanying drawings, Figure 1 is a view showing one arrangement of signals to which my invention may be applied. Fig. 2 is a diagrammatic view showing one arrangement of apparatus and circuits for the control of signals 5 and 7 in Fig. 1 and embodying my invention.

Similar reference characters refer to similar parts in both of the views.

Referring first to Fig. 1, the reference character 15 designates the track rails of a portion of a single track railway, which is divided by passing sidings M, N and O into two stretches A—D and E—H. Stretch A—D is further divided, by insulated joints 2, into a number of blocks A—B, B—C and 35 C—D, while stretch E—H is similarly divided into blocks E—F, F—G and G—H.

Traffic through the stretch E—H from east to west is governed by a plurality of signals 1, 3 and 5, while traffic through this 40 same stretch in the opposite direction is governed by signals 4, 6 and 8. Stretch A—D is similarly provided with signals 9, 11, 13, 12, 14 and 16. The passing siding N is protected by signals 7 and 10. As here 45 shown, a pair of opposing signals is located adjacent each end of each block, although I do not desire to be limited to this particular location and distribution of the signals.

The signals for stretch A—D are so controlled that when a train moving toward the east enters this stretch, signals 9, 11 and 13 are placed at "stop" and signal 9 is held at stop until the train passes out of the stretch, thus prohibiting a westbound train

from entering the stretch while the east-bound train is anywhere in the stretch. As the eastbound train enters the stretch, it also causes signal 16 to indicate "stop," and as it passes signals 14 and 12 these signals are successively caused to change to "stop" 60 indication. When the entire train passes out of block A—B, signal 16 changes to the "caution" indication, and when the entire train passes out of block B—C, this signal returns to the full "proceed" indication. 65 Signal 14 changes to "caution" when the train leaves block B—C, and to "proceed" when the train leaves block C—D. Two or more trains may, therefore, follow each other through the stretch under the same signal 70 protection as is customarily provided on double track roads. Similarly, when a westbound train enters stretch A—D, signals 9, 12, 14 and 16 are placed at stop, and signal 9 subsequently changes successively to "caution" and "proceed." Signal 11 changes to 75 stop when it is passed by the train, and subsequently changes to "caution" and "proceed" successively.

The signals for stretch E—H are controlled in the same manner as the signals for stretch A—D.

The operation of the signals which I have just outlined may be accomplished by several different arrangements of apparatus and circuits, such, for example, as the arrangements shown in Letters Patent of the United States, Nos. 1,204,998 and 1,233,488, granted to me on November 14, 1916, and on July 17, 1917 respectively. I do not wish to be 90 limited however, to any particular arrangements of apparatus and circuits for accomplishing this signal operation.

With the arrangement of circuits shown herein, whenever signal 9 indicates "stop" 95 signal 7 indicates "caution," and whenever signal 7 indicates "stop," signal 5 indicates "caution." The manner in which this control is accomplished will be explained hereinafter. It is desirable, however, that when 100 an eastbound train occupies stretch A—D, signal 5, as well as signal 7 should indicate "caution," but that when a westbound train has passed signal 9, thus allowing signal 7 to change to "caution," signal 5 should return to the full "proceed" position. The reason for this is as follows: Assume that signal 5 indicates proceed while signal 9 is

at stop, and that two trains moving in opposite directions approach siding N. If the eastbound train should pass signal 9 just after the westbound train had passed signal 5 (indicating proceed), the westbound train would receive a stop indication at signal 7 without having been previously warned by a caution indication at signal 5. However, if two westbound trains are moving along the track from H to A, it is desirable that signal 5 should change to proceed indication as soon as the first train has passed signal 9, in order to avoid any unnecessary delay to the second train by a caution indication at signal 5.

The object of the present invention is the provision of novel and simple means for accomplishing the desired control of signal 5.

Referring now to Fig. 2, the main track of the siding N is provided with a track circuit comprising a battery b^{10} and a track relay T^{10} . Block E-F is divided into two sections E-K and K-F, each of which is provided with a track circuit comprising track relays T^8 and T^5 respectively.

Signal 7 is controlled by a signal relay R^7 , which is responsive to reversals of current. The "caution" indication circuit for this signal is from battery Z^7 through wire 17, neutral contact 18 of relay R^7 , wire 19, signal 7, wire 20, neutral contact 21 of relay R^7 , and wires 22 and 23 to battery Z^7 . The "proceed" indication circuit for this signal is the same as the caution circuit up to and including contact 18, then through wire 24, polarized contact 25, wire 26, signal 7, thence as before to battery Z^7 . Signal 7, consequently, indicates "proceed" when relay R^7 is energized in such direction as to close contact 25 (which I will call the normal direction of energization), "caution" when the relay is energized in the reverse direction, and "stop" when the relay is deenergized.

Signal 5 is similarly controlled by a signal relay R^5 , the caution circuit for this signal including neutral contacts 32 and 33, and the proceed circuit including a polarized contact 34 which is closed when the relay is energized in normal direction but not in reverse direction.

Signal 9 is controlled by a signal relay R^9 in the same manner as signal 7 is controlled by relay R^7 . Relay R^9 is controlled by suitable apparatus in stretch A-D, for causing the operation of signal 9 hereinbefore referred to, this controlling apparatus including a contact 27 of a track relay T^9 , which latter relay is part of a track circuit for section K'-D of block C-D.

Signal relay R^7 is provided with a circuit which is controlled by the track relay T^{10} and by a pole-changer V^9 operated by signal 9, this pole-changer being reversed while the signal is moving between the "stop" and "caution" positions. This circuit, when the

pole-changer is in the position shown, is from battery Z^9 through wires 35 and 36, pole-changer V^9 , wire 37, contact 38, wire 39, relay R^7 , wire 40, pole-changer V^9 , and wire 41 to battery Z^9 . Current of normal polarity is then supplied to relay R^7 . That is, when signal 9 indicates "proceed" or "caution," relay R^7 is energized in the normal direction so that signal 7 then indicates proceed; but when signal 9 indicates "stop," relay R^7 is energized in the reverse direction, so that signal 7 then indicates "caution;" assuming in both cases, of course, that block D-E is unoccupied.

Operatively connected with signal 7 are two pole-changers W^7 and V^7 . Pole-changer W^7 is arranged to reverse while signal 7 is moving between the "proceed" and the "caution" positions, while pole-changer V^7 is arranged to reverse while signal 7 is moving between "caution" and "stop" positions.

Signal relay R^5 , which controls signal 5, is provided with a circuit which at times is governed by pole-changer W^7 , and at other times by pole-changer V^7 . The selection is accomplished by a stick relay J . When relay J is deenergized, relay R^5 is controlled by pole-changer W^7 , but when relay J is energized, relay R^5 is disconnected from pole-changer W^7 and is connected with pole-changer V^7 . The circuit for relay R^5 when pole-changer W^7 is included therein and is in the position shown, is as follows: from battery Z^7 , through wires 17, 28, 29 and 30, left hand arm of pole-changer W^7 , wire 31, back contact 42 of relay J , wire 43, contact 44 of track relay T^5 , wire 45, contact 46 of track relay T^5 , wire 47, relay R^5 , wire 48, back point of contact 49 of relay J , wire 50, right hand arm of pole-changer W^7 , wires 51, 52, 22 and 23 to battery Z^7 . The circuit for relay R^5 when pole-changer W^7 is reversed will be apparent without tracing in detail. Assuming now that relay J is energized, and that pole-changer V^7 is in the position shown in the drawing, the circuit for relay R^5 is then from battery Z^7 , through wires 17, 28 and 53, left hand arm of pole-changer V^7 , wire 54, front point of contact 42 of relay J , theace as before through relay R^5 to the front point of contact 49 of relay J , wire 55, right hand arm of pole-changer V^7 , and wires 56, 52, 22 and 23, to battery Z^7 . The circuit for relay R^5 when pole-changer V^7 reverses will be apparent without tracing in detail.

When pole-changer W^7 is in control of the circuit of relay R^5 , and is in the position shown, that is, when signal 7 is in the "proceed" position, current of normal polarity is supplied to relay R^5 so that this relay is energized in the normal direction and signal 5 indicates "proceed." When, however, pole-changer W^7 reverses, that is, when signal 7

indicates "caution" or "stop," relay R^5 is energized in the reverse direction so that signal 5 indicates "caution." When pole-changer V^7 is in control of relay R^5 and is 5 in the position shown, that is, when signal 7 indicates "proceed" or "caution," current of normal polarity is supplied to relay R^5 , so that signal 5 indicates "proceed." When signal 7 occupies the "stop" position, however, 10 so that pole-changer V^7 is reversed, current of reverse polarity is supplied to relay R^5 , so that signal 5 indicates "caution."

The stick relay J is provided with a pick-up circuit which passes from battery Z^7 , 15 through wires 17, 28, 29, 57 and 57^a, contact 58, wire 59, back point of contact 60 of relay R^7 , polarized contact 61 of relay R^7 , winding of relay J , and wires 63 and 23 to battery Z^7 . Contact 58 is closed momentarily 20 while signal 7 is moving from the "proceed" or "caution" position to the "stop" position, consequently, this pick-up circuit is closed momentarily when a train moving toward the west enters block D-E. Such a 25 train, of course, opens track relay T^{10} , which, in turn, opens relay R^7 , so that contact 60 is closed and contact 61 remains closed, provided that relay R^7 was previously energized in the normal direction. The holding 30 circuit for relay J is from battery Z^7 , through wires 17, 28, 29 and 57, contact 64, wire 65, contact 66 of relay J , wire 67, winding of relay J , and wires 63 and 23 to battery Z^7 . Contact 64 is closed while signal 35 7 indicates either "stop" or "caution" consequently, this holding circuit remains closed until a train moving toward the west passes signal 11 in Fig. 1.

The operation of the system is as follows: 40 When there is no train on the track between points A and F in Fig. 1, the parts of the apparatus are in the positions in which they are shown in Fig. 2, so that signals 9, 7 and 5 indicate "proceed." Relay J is deenergized so that relay 5 is controlled 45 by pole-changer V^7 . If now a train moving toward the east enters stretch A-D, it causes signal 9 to change to the "stop" position, and this movement of signal 9 reverses 50 pole-changer V^9 , so that signal relay R^7 becomes energized in the reverse direction, thus causing signal 7 to move to the "caution" position. This movement of signal 7 55 reverses pole-changer V^7 , so that relay R^5 becomes energized in reverse direction, thus causing signal 5 to move to the "caution" position. The signals remain in these positions until the train enters block D-E, whereupon signal relay R^7 becomes deenergized, due to the opening of track relay T^{10} , 60 so that signal 7 moves to the "stop" position. This movement of signal 7 causes no change in the position of signal 5. The deenergization of relay R^7 due to the entrance 65 of the train upon block D-E does not close

the pick-up circuit for relay J , because relay R^7 was previously energized in the reverse direction, so that its polarized contact 61, which is included in this pick-up circuit, is open. As the train enters block E-F, 70 signal 5, of course, moves to the "stop" position, because relay R^5 becomes deenergized due to the opening of track relay T^8 .

I will now assume that the track between points A and F is unoccupied and that a 75 train moving toward the west enters block E-F. The consequent opening of track relay T^8 causes signal relay R^5 to become deenergized, whereby signal 5 moves to the "stop" position. As the train proceeds 80 through the block E-F, track relay T^8 opens, and track relay T^5 closes, but this causes no change in the condition of the apparatus. As the train enters block D-E, it opens track relay T^{10} , which, in turn de- 85 energizes relay R^7 , whereby signal 7 moves to the stop position. During this movement of signal 7, contact 58 is closed momentarily, and, contacts 60 and 61 of relay R^7 being already closed, the pick-up circuit for relay J 90 is closed momentarily. Contact 64, operated by signal 7, being closed after the signal reaches the caution position, the holding circuit for relay J is closed as soon as the relay itself closes. Contacts 42 and 49 of 95 relay J then disconnect signal relay R^5 from pole-changer V^7 and connect this relay with pole-changer V^7 . Signal 7 being in the "stop" position, it follows that as soon as the entire train has passed out of block 100 E-F, current of reverse polarity is supplied to signal relay R^5 , so that signal 5 moves to the "caution" position. As the train passes out of block D-E and into block C-D, signal 7 moves to the "caution" position, and 105 this movement reverses pole-changer V^7 , so that current of normal polarity is then supplied to signal relay R^5 , whereby signal 5 moves to the "proceed" position. Relay J , of course, remains energized while signal 7 110 is in the "caution" position, because the holding circuit of this relay is closed at contact 64. As the train passes signal 11 (Fig. 1), signal 9 moves to the "caution" position, thus reversing pole-changer V^9 , so that signal relay R^7 becomes energized in normal 115 direction and signal 7 then moves to the "proceed" position. This movement of signal 7 opens contact 64, which in turn opens the holding circuit for relay J , so that this 120 relay then becomes deenergized. Pole-changer V^7 is then disconnected from relay R^5 and pole-changer V^7 is thrown into the circuit of this relay, but inasmuch as signal 7 now occupies the "proceed" position, no 125 change occurs in the condition of relay R^5 , and so signal 5 remains in the "proceed" position. After the train passes signal 13 (Fig. 1), signal 9 moves to the "proceed" 130 position, so that all parts of the apparatus

shown in Fig. 2 are again in the positions in which they are illustrated.

Where in the accompanying claims I have used the expression "a portion of railway track comprising three successive blocks," the blocks referred to are blocks E—F, D—E and C—D, these being the first, second and third blocks respectively. The signals for the first and second blocks are signals 5 and 7 respectively.

Although I have herein shown and described only one form of signaling system embodying my invention, it is understood that various changes and modifications may 15 be made therein within the scope of the appended claims without departing from the spirit and scope of my invention.

Having thus described my invention, what I claim is:

20 1. In combination, a portion of railway track comprising three successive blocks, a first and a second signal for the first and second blocks respectively, each adapted to indicate "stop," "caution" and "proceed," a 25 relay responsive to reversals of current for controlling said first signal, train controlled means for causing said second signal to indicate "caution" or "proceed" according to the presence or absence of a train in the 30 third block, the second block being unoccupied, two pole-changers operated by the second signal, the first of which reverses while the signal is between "proceed" and "caution" positions and the second of which 35 reverses while the signal is between "caution" and "stop" positions, a stick relay, means for energizing said stick relay when a train enters the second block moving toward the third and for keeping it energized until the 40 train leaves the third block, and means controlled by said stick relay for placing said relay for the first signal under control of said first pole-changer or said second pole-changer, according as the stick relay is de- 45 energized or energized.

2. In combination, a portion of railway track comprising three successive blocks, a first and a second signal for the first and second blocks respectively, each adapted to indicate "stop," "caution" and "proceed," a 50 relay responsive to reversals of current for controlling said first signal, train controlled means for causing said second signal to indicate "caution" or "proceed" according to the presence or absence of a train in the 55 third block, the second block being unoccupied, two pole-changers operated by the second signal, the first of which reverses while the signal is between "proceed" and "caution" positions and the second of which 60 reverses while the signal is between "caution" and "stop" positions, means for normally controlling said relay for the first signal by said first pole-changer, and means controlled by a train entering the second block, moving toward 65 the third for removing said relay from control by said first pole-changer and placing it under control by said second pole-changer, the current which is then supplied to the signal relay being of normal or reverse polarity according as the second signal is in "caution" or "stop" position.

66 3. A railway signaling system comprising two successive signals, each adapted to indicate "stop," "caution" and "proceed," apparatus responsive to reversals of current for controlling the rear of said signals, two 70 pole-changers operated by the forward signal, one of which reverses while the signal is between "proceed" and "caution" positions, and the other while the signal is between "caution" and "stop" positions, and 75 train controlled means for causing said apparatus to be controlled by one of said pole-changers or the other.

76 4. In combination, a portion of railway track comprising three successive blocks, a 80 first and a second signal for the first and second blocks respectively, each adapted to indicate "stop," "caution" and "proceed," train controlled means for causing said second signal to indicate "caution" or "proceed" according to the presence or absence of a train in the 85 third block, the second block being unoccupied, a signal relay responsive to reversals of current for controlling said first signal whereby such signal 90 indicates "proceed" or "caution" according as said signal relay is supplied with current of normal or reverse polarity, two pole-changers operated by said second signal the first of which reverses while the signal is 95 between "proceed" and "caution" positions, and the second while the signal is between "caution" and "stop" positions, means for normally controlling said signal relay by said first pole-changer the current which is 100 then supplied to the signal relay being of normal or reverse polarity according as the second signal is in "proceed" or "caution" position, and means controlled by a train entering the second block, moving toward 105 the third for removing said relay from control by said first pole-changer and placing it under control by said second pole-changer, the current which is then supplied to the signal relay being of normal or reverse polarity according as the second signal is in "caution" or "stop" position.

110 5. In combination, a portion of railway track comprising three successive blocks, a first and a second signal for the first and second blocks respectively, a stick relay, means controlled by a train passing along said track from the first block toward the third for energizing said stick relay, and holding it energized until the train leaves 115 the third block, said relay remaining de-energized during the passage of a train in the other direction, and means controlled by said stick relay and by said second signal and operating when the latter signal indi- 120 125 130

cates "caution" to cause the first signal to indicate "proceed" or "caution" according as the stick relay is energized or deenergized.

5 6. A railway signaling system comprising two successive signals, means responsive to reversals of current for controlling the rear of said signals, two pole-changers operated by the forward signal and arranged to reverse at different positions in the movement

of the signal, and train controlled means for causing said first mentioned means to be controlled by one pole-changer or the other.

In testimony whereof I affix my signature 15 in presence of two witnesses.
